UNITED STATES PATENT OFFICE.

HARRY EASTWOOD, OF FRESNO, CALIFORNIA.

ELECTRIC FISHING-TOOL.

974,760.

Specification of Letters Patent. Patented Nov. 1, 1910.

Application filed February 2, 1910. Serial No. 541,577.

To all whom it may concern:

Be it known that I, HARRY EASTWOOD, a citizen of the United States, residing at Fresno, in the county of Fresno and State of California, have invented new and useful Improvements in Electric Fishing-Tools, of which the following is a specification.

This invention relates to fishing-tools such as are employed in well-drilling operations 10 in recovering drill bits, reamers and the like which have been lost in the bottom of the well.

It is the object of this invention to provide a simple, practical fishing-tool in which 15 electro-magnetic means are employed for engaging or picking up and recovering the metallic implements or broken parts lost in the well.

The invention consists of the parts and 20 the construction and combination of parts as hereinafter more fully described and claimed, having reference to the accompanying drawings, in which—

Figure 1 is a vertical section of the invention on the line X—X, Fig. 2. Fig. 2 is 25 a cross-section on the line Y—Y, Fig. 1. Fig. 3 is a cross-section on the line Z—Z, Fig. 1.

In the drawings, A is a waterproof non- 30 magnetic casing in which is contained a series of soft iron cores 2 suitably wound with wire at 3 to form electro-magnets. The cores 2, in this case four in number, are mounted in a soft iron, tapered armature 35 plug 4 at their lower ends, which plug is divided centrally by a non-conducting plate 5 so as to form a pair of armature sections, in each of which a pair of the electro-magnets, composed of a core 2 and helical wire 40 3, are mounted. The upper ends of the cores 2 are mounted in a non-conducting disk 6 which fits into the upper end of the casing A.

7 are draw-bolts which have one of their 45 ends threaded into the tapered plug or armature sections 4, and, extending upward, pass through the disk 6 and upper end of the casing A. The upper ends of the bolts 7 are threaded to receive nuts 8 which on being screwed onto the bolts 7, draw the tapered plug 4 tight into the correspondingly 50 tapered lower end of the casing A, so as to form a water-tight joint at this point. A rod 9, solid or tubular, passes through the upper end of the casing A and is threaded 55 into the disk 6; a suitable rope or cable (not

shown) being attached to this rod, by means of which the tool is manipulated in the well.

As a means of rendering the upper end of the casing water-tight, I employ a conical cap 9' which is provided with a flange 10 on its lower edge and closely fits the rod 9 at its apex, through which the rod extends. The cap 9' is adapted to be secured to the end of the casing A by suitable means, as the screws 11 which pass through the flange 10 and are threaded into the casing A. A gasket 12 is interposed between the flange 10 on the cap 9' and the casing A, so as to make a water-tight joint at this point. To insure that no liquid can enter the casing A 60 along the rod 9, a collar 13 is secured to the latter so as to form a shoulder which is adapted to bear against the upper edge of the cap 9'; a gasket 14 being interposed between the cap 9' and the shoulder or collar 70 13, so that by screwing the rod 9 further into the disk 6 a tight joint will be obtained. The terminals of the magnet wires 3 pass through suitable bores in the disk 6 and connect to a plug 15 which screws into a 80 socket 16 on the cap 9'. Plug 15 is connected to suitably insulated feed wires 17 which lead to any desired and suitable source of electrical energy; and the usual switches (not shown) are provided for cutting off 85 and controlling the circuits affecting the coils 3.

In operation, the tool is lowered into a well in any suitable manner. When the desired point is reached the armature plug 90 4 is magnetized by directing a current of electric energy through the magnets 3, and thus attract such metallic tools, or parts, as may be in the bottom of the well; which articles, on being picked up, may be drawn out 95 of the well with the fishing-tool and removed.

In event the lost tool is of considerable 100 length and should be disposed at an angle or crosswise of the well bore beneath the well casing, thereby rendering it impossible to withdraw it in that position, one side only of the armature 4 is magnetized, and to such extent that it will not have sufficient power 105 to entirely lift the tool, but will allow the latter to slide more or less on the magnetized surface of the armature. In this manner, when the tool is attracted by the armature, its heaviest end will tend to keep its position, and as the armature 4 is gradually lifted up 110

- ward, the lighter end of the tool will tend to follow the magnet, and occasionally slip or slide thereon, until the end of the tool is reached. The tool will then have assumed a nearly perpendicular position, whereupon the other half of the armature is magnetized, so that sufficient power will be developed with which to lift the tool and remove it from the well.
- 10 Having thus described my invention, what I claim and desire to secure by Letters Patent is—
1. A fishing-tool consisting of a water-proof casing with a removable, sectional armature plug in the bottom, and means within the casing for magnetizing said armature sections.
  2. A fishing-tool comprising a non-magnetic tubular casing having an armature plug at one end, electro-magnets connected with said plug and housed within the casing, draw-bolts passing through the casing and seated in the plug to hold the latter in position, and electrical connections with the magnets extending out exterior of the casing.
  3. An electrical fishing-tool comprising a non-magnetic water-tight casing having at its lower end a removable, tapered armature forming a closure, and electro-magnetic means housed in the casing and connected with said armature.
  4. An electrical fishing-tool comprising a non-magnetic water-tight casing having at its lower end a removable, tapered armature forming a closure, and electro-magnetic means housed in the casing and connected with said armature, said armature made in sections insulated from each other and adapted to be separately energized.
  - 40 5. A fishing-tool comprising a water-tight casing, the lower end of which is provided with a removable, tapered armature plug, said plug made in sections, and an electro-magnet for each armature section, said magnets housed within the casing.
  - 45 6. A fishing-tool comprising a water-tight casing, the lower end of which is provided with a removable, tapered armature plug, said plug made in sections, an electro-mag-

net for each armature section, said magnets housed within the casing, and draw-bolts passing through the casing and seating in the armature sections to hold the latter in place.

7. A fishing-tool comprising a water-tight tubular casing having a removable, tapered armature plug fitting its lower end, a rod passing through the top of the casing and screwing into a block within the casing, a conical water-tight cap fitting around the rod and over the top of the casing, with means for forming a tight joint, and electro-magnets within the casing and connected with the armature.

8. A fishing-tool comprising a water-tight tubular casing having a removable, tapered armature plug fitting its lower end, a rod passing through the top of the casing and screwing into a block within the casing, a conical water-tight cap fitting around the rod and over the top of the casing, with means for forming a tight joint, electro-magnets within the casing and connected with the armature, said armature made in sections insulated from each other, and means for holding the sections in place.

9. A fishing-tool comprising a water-tight tubular casing having a removable, tapered armature plug fitting its lower end, a rod passing through the top of the casing and screwing into a block within the casing, a conical water-tight cap fitting around the rod and over the top of the casing, with means for forming a tight joint, electro-magnets within the casing and connected with the armature, draw-bolts connected with the armature passing through the casing, and means outside the casing acting on the draw-bolts and coacting therewith to hold the armature in position.

In testimony whereof I have hereunto set my hand in the presence of two subscribing witnesses.

HARRY EASTWOOD.
